UNITED STATES PATENT OFFICE.

HAROLD S. ADAMS, OF NEW ROCHELLE, NEW YORK, AND LUDWIG MEUSER, OF BOUND-BROOK, NEW JERSEY, ASSIGNORS TO THE NAUGATUCK CHEMICAL COMPANY, OF NAUGATUCK, CONNECTICUT, A CORPORATION OF CONNECTICUT.

METHOD FOR TREATING HEAVY VEGETABLE OILS.

Application filed January 13, 1926. Serial No. 81,089.

This invention relates to a method for treating heavy vegetable oils, more particularly to a method for cracking castor oil to obtain heptaldehyde.

Until comparatively recently the majority of the heavier aldehydes were mere laboratory curiosities, but in more recent years they have become of considerable commercial importance, for instance in making vulcanization accelerators by forming condensation products of the aldehydes with various amines. As an example, in patent to Cadwell, No. 1,417,970, granted May 30, 1922, there are disclosed various condensation products of aldehydes and amines, among which are the condensation product of heptaldehyde and aniline. The laboratory method of preparing heptaldehyde, and as far as we are aware the only one used commercially to any extent, is to rapidly heat castor oil in bulk in a glass vessel, in vacuum or at atmospheric pressure, to a temperature of 450° to 500° C., the castor oil being thereby cracked and producing heptaldehyde among the decomposition products. This method of preparing heptaldehyde is wasteful by reason of the relatively small yield, is more or less dangerous, and is open to numerous other objections. When the castor oil is rapidly heated it tends to foam and at the same time by reason of polymerization the liquid becomes very viscid and soon sets to a gel which is rendered spongy or porous by the decomposition gases which are distributed through it. It is impossible to maintain the temperature of the body of this gel to the required degree to crack it since its porous form renders it a very poor conductor of heat, and by reason of the large increase in volume the receptacle is liable to be burst or the outlet to the condenser blocked or both.

An object of our invention is to provide an improved method for cracking heavy vegetable oils such as castor oil.

Another object is to provide an improved method for obtaining heptaldehyde from castor oil.

Other objects will appear from the detailed descriptions and claims.

Without intention to limit the invention other than as required by the prior art, it

consists broadly in heating a heavy vegetable oil while in a thinly extended or otherwise attenuated form to a temperature sufficiently high to decompose the oil and completely volatilize the decomposition products, continuously supplying oil at a rate such that there will be no residue of undecomposed oil, and separating the desired materials from the decomposition products.

For a detailed disclosure of the nature and objects of the invention reference is had to the accompanying specification and drawing, in which latter,

The figure is a part longitudinal section and part elevation of a suitable apparatus.

The apparatus for cracking the oil will first be described, and in this apparatus the numeral 1 represents a furnace supported upon legs 2, the outer casing of the furnace being formed of any suitable heat insulating material such as silocel brick 3. Within the silocel brick is a lining 4 of fire brick forming a heating chamber 5, and in this chamber is disposed an electric heating element 6. However, the furnace may be heated in any other desired manner. Passing through the heating chamber 5 is a passageway or chamber for the oil to be cracked, which passageway in the present instance is formed of an inclined nichrome pipe. However, any other suitable material which is inert to the decomposition products may be employed, such as duriron or silica. At the upper or inlet end of the pipe 7 a fitting 8 is connected in which is disposed an S pipe 9 to form a liquid seal, while to the outer end of this pipe a sight feed cup 10 is connected. A graduated supply of the oil to be cracked is supplied to the cup 10 by the valve controlled pipe 11, leading from a tank 12. The lower end of pipe 7 is connected to an over flow pipe 13 extending into a sump 14 and opening into the latter adjacent to the bottom, so as to maintain a liquid seal. A second overflow pipe 15 extends from the upper portion of the sump 14 and delivers into a receptacle 16. Leading from the connection 8 is an exhaust pipe 17 for the decomposition products, which pipe is connected to a condenser 18, and the latter delivers the condensate through a pipe 19 into a receiver 20. Attached to the lid of the receiver 20 is an ex-

haust pipe 21 for conducting away any fixed gases. The condenser pipes and connections thereto are preferably of duriron.

In carrying out the process as applied for instance to the cracking of castor oil, the furnace is heated by the electric heating unit 6 and a regulated quantity of castor oil is fed into the cracking pipe 7 from the supply pipe 11. The temperature of the pipe 7 is maintained at from 500° to 600° C., and castor oil is supplied to the pipe in a small stream so regulated that it is continuously and completely decomposed and the decomposition products volatilized without any residue of undecomposed or partly decomposed oil. If by reason of improper regulation there should be a residue of oil, the same flows through the pipe 13 and into the sump 14 to form a liquid seal for the apparatus. However, under proper operating conditions there should be no residue and if so the seal may be otherwise provided. The products of the decomposition are undecylenic acid, acrolein, various hydrocarbons, fixed gases, and a relatively large proportion of heptaldehyde mixed to some extent with other aldehydes and ketones. The decomposition products pass through pipe 17 to the condenser 18 and are collected in the receptacle 20, while the fixed gases are exhausted through pipe 21. The condensate is then steam distilled, and in this operation the undecylenic acid, being non-volatile in steam, is left behind in the still. The acrolein has a relatively low boiling point (52.4° C.) and is appreciably soluble in water, while the heptaldehyde has a much higher boiling point (153.5° C.) and is insoluble in water. Hence by maintaining the condenser of the still at a relatively low temperature, for instance 65° to 75° C., the heptaldehyde is condensed and the acrolein either dissolves in water present or passes off as vapor. The crude heptaldehyde product thus recovered is a pale yellow, water-insoluble liquid which consists essentially of heptaldehyde. The yield of crude heptaldehyde is about 25% by weight of the castor oil, and this product analyzes about 85% pure heptaldehyde.

It is desirable that the tube 7 be formed of a material which is inert to the decomposition products, since if some other material such as cast iron be used it has been found that the yield of heptaldehyde is considerably reduced. Steel or wrought iron tubes may be used, but require exact temperature conditions to obtain a satisfactory yield, and are therefore more critical to operate than one formed of non-catalytic material. The best temperature for the decomposition is at about 450° to 500° C., and as before stated, by properly balancing the temperature and the rate of supply of the castor oil the latter will be completely decomposed

without any overflow. While in the present specific apparatus the castor oil has been permitted to flow in a small stream through a heated inclined pipe, it is obvious that any other apparatus may be utilized by which the castor oil in attenuated or finely divided form is subjected to the proper temperature. By the invention all formation of gel and consequent useless residue is avoided as well as risk of explosion, and at the same time a largely increased yield of heptaldehyde is obtained.

While in the specific example given, the process has been applied to the cracking of castor oil, it is obvious that the broad process is equally well applicable to the cracking of other heavy vegetable oils, and it is not desired to limit the invention otherwise than as set forth in the appended claims.

Having thus described our invention what we claim and desire to protect by Letters Patent is:

1. The method of treating heavy vegetable oils which comprises introducing the oil in attenuated form into a heated zone in the absence of air or catalytic agents, and maintaining a relatively high temperature in said zone sufficient to substantially completely decompose the oil and volatilize the decomposition products, said temperature being below the decomposition temperature of heptaldehyde.

2. The method of treating heavy vegetable oils which comprises slowly passing castor oil in attenuated form through a heated zone in the absence of air or catalytic agents and maintaining a relatively high temperature in said zone sufficient to substantially completely decompose the oil and volatilize the decomposition products, said temperature being below the decomposition temperature of heptaldehyde.

3. The method of treating heavy vegetable oils which comprises slowly flowing castor oil in a thin stream through a passage having walls of non-catalytic material, and maintaining a relatively high temperature in said passage sufficient to completely decompose the oil and volatilize the decomposition products, said temperature being below the decomposition temperature of heptaldehyde.

4. The method of treating heavy vegetable oils which comprises heating castor oil in attenuated form in the absence of catalytic agents to a cracking temperature not substantially over 500° C. and recovering a decomposition product therefrom.

5. The method of treating heavy vegetable oils which comprises continuously flowing castor oil in a thin stream through a passage of limited cross sectional area composed of material inert to heptaldehyde about 450° C. externally heated to 500° to 600° C., con-

densing the decomposition products, steam distilling said products to separate heptaldehyde and acrolein from undecylenic acid, and separating heptaldehyde from the acrolein by passing through a condenser heated above the boiling point of the acrolein.

6. The method of treating heavy vegetable oils which comprises continuously flowing castor oil in a thin stream through a tube of non-catalytic material heated to 500° to 600° C., to thereby substantially completely decompose the oil and volatilize the decomposition products, condensing the decomposition products, distilling at a temperature below the boiling point at undecylenic acid, thereby separating out the latter, condensing the distillate in the presence of water at a temperature below the boiling point of heptaldehyde, and recovering heptaldehyde from the condensate.

7. The method of treating heavy vegetable oils which comprises heating castor oil in the absence of catalytic agents in a relatively thinly extended form to a temperature above 450° C., and recovering heptaldehyde from the decomposition products.

8. The method of treating heavy vegetable oils which comprises continuously supplying

castor oil in a relatively thinly extended form to a non-catalytic cracking zone heated to substantially 450-500° C., and recovering heptaldehyde from the decomposition products.

9. The method of treating heavy vegetable oils which comprises passing castor oil through a non-catalytic cracking zone heated above 450° C. at a maximum rate such that the oil is completely decomposed and the decomposition products volatilized, and separating the decomposition products.

10. The method of treating heavy vegetable oils which comprises passing castor oil in an attenuated form through a chamber formed of a non-catalytic material inert to heptaldehyde above 450° C., heating the chamber above such temperature, and recovering heptaldehyde from the decomposition products.

Signed at New York, county of New York, and State of New York, this 31st day of December, 1925.
